(57) **CLAIM**

The ornamental design for an electrical cord organizer, as shown and described.

DESCRIPTION

FIG. 1 is a perspective view from the front, top and right side of an electrical cord organizer, showing my new design;

FIG. 2 is a perspective view from the rear, top and right side thereof;

FIG. 3 is an elevational view from the front thereof;

FIG. 4 is a top plan view, the bottom plan view being a mirror image, thereof; and,

FIG. 5 is an elevational view from the right side thereof.
